ATTORNEYS.

UNITED STATES PATENT OFFICE.

CHARLES G. WHEELAND, OF SAN FRANCISCO, CALIFORNIA.

MEDICINE DROPPER.

Application filed April 16, 1928. Serial No. 270,551.

The present invention relates to improvements in medicine droppers, and it consists in the combinations, constructions, and arrangements hereinafter described and 5 claimed.

An object of my invention is to provide a medicine dropper that has means for preventing fluid sucked up into the tube from being drawn into the rubber bulb. This gives a 10 longer life to the bulb, because it is not subjected to the action of the medicinal fluid.

A further object of my invention is to provide a device of the type described which is extremely simple in construction and which 15 will not affect the normal operation of the device.

Other objects and advantages will appear in the following specification, and the novel features of the device will be particularly 20 pointed out in the appended claims.

My invention is illustrated in the accompanying drawing forming a part of this application, in which

Figure 1 is a vertical section through the 25 device showing the bulb partially deflated and the fluid drawn up into the tube, and

Figure 2 shows how the fluid is prevented from entering the bulb.

In carrying out my invention, I provide 30 a tube 1 which may be made of any material desired. This tube is provided with a reduced outlet end 2 and a conical-shaped upper end 3. The openings 4 and 5 at each end of the tube are made small enough to prevent 35 the passage of a floating stopper 6. This stopper may be made of cork or any other material that will be buoyant enough to float upon a liquid.

The tube has a shoulder 7 for receiving the 40 open end of a rubber bulb 8.

From the foregoing description of the various parts of the device, the operation thereof may be readily understood.

The device operates in the usual manner, 45 that is, when the bulb 8 is depressed and the

end 2 inserted in a liquid, a releasing of the bulb will create sufficient suction to draw a liquid 9 up into the tube 1. A pressing of the bulb 8 to collapse it will expel the fluid from the tube.

When the tube is empty, the member 6 will be disposed at the bottom and will close the opening 4. When the bulb 8 is depressed and then released for sucking a fluid up into the tube 1, the member 6 will float upon the top 50 of the fluid as shown in Figure 1. When the tube is entirely filled, the float will be forced into the conical-shaped end 3 and will close the opening 5. This will prevent the fluid from entering the bulb 8. A pressure upon 55 the bulb to expel the fluid from the tube will force the member 6 down into the tube and at the same time will expel the fluid from the tube. As the fluid is expelled from the tube, the member 6 will float upon the surface until 60 it reaches the reduced end 2. In this way practically the entire contents of the tube may be expelled and only a drop or two will remain in the reduced end and below the member 6.

Although I have shown and described one embodiment of my invention, it is to be understood that the same is susceptible of various changes, and I reserve the right to employ such changes as may come within the 70 scope of the appended claims.

I claim:

1. A medicine dropper comprising a tube, a collapsible bulb secured thereto, and a member actuated by a liquid drawn into the tube 80 for sealing the upper end of the tube for preventing passage of the liquid into the bulb.

2. A medicine dropper comprising a tube having reduced ends, a movable stopper disposed in said tube for closing either end, and a collapsible bulb covering one end of the tube.

CHARLES G. WHEELAND.
